(57) **CLAIM**

The ornamental design for a flying ring as shown and described.

DESCRIPTION

FIG. 1 is a top perspective view of a flying ring showing our new design;

FIG. 2 is a top planar view thereof;

FIG. 3 is a side view thereof;

FIG. 4 is a bottom perspective view thereof;

FIG. 5 is a bottom planar view thereof;

FIG. 6 is a bottom planar view thereof; and,

FIG. 7 is a bottom planar view thereof.

The broken lines shown in the drawings illustrate portions of a flying ring that form no part of the claimed design.
